ABSTRACT

Novel, nontoxic, nonmercurial diuretic compounds are disclosed, which are potassium derivatives of 2-phenyl-6-sulphamyl-7-chloro-1,2,3,4-tetrahydro-4-quinazolinone. The monopotassium derivative is obtained by replacing either hydrogen of the sulphamyl group of the starting quinazolinone by a potassium atom, whereas the dipotassium derivative is obtained by replacing either hydrogen of the sulphamyl group of the starting quinazolinone and also the hydrogen atom lying in the 3-position of the tetrahydro-quinazolinone ring of same starting quinazolinone by a potassium atom each.

**POTASSIUM DERIVATIVES OF
2-PHENYL-6-SULPHAMYL-7-CHLORO-1,2,3,4-
TETRAHYDRO-1-QUINAZOLINONE**

BACKGROUND OF THE INVENTION

This invention relates to non-mercurial diuretics and, more particularly, to compounds capable of enhancing the diuresis without exhibiting obnoxious side effects.

PRIOR ART

It is known that 2-phenyl-6-sulphamyl-7-chloro-1,2,3,4-tetrahydro-4-quinazolinone has a considerable diuretic activity (Biressi et al. - Il Farmaco - Ed.Sc., 24, 199 (1969); Barbi et al., ibid., 24, 496 (1969)).

The above named compound has proven to be capable, under different experimental conditions, of enhancing the diuresis and also both the elimination of sodium and potassium ions. It has been ascertained, moreover, that the elimination of potassium ions had a slower increase, as the dosage was increased, than that of sodium ions and exhibited a tendency towards a maximum boundary value: this fact was doubtless a favorable circumstance from the clinical viewpoint. The above identified quinazolinone, in addition, displayed the above described diuretic action while being completely inactive as a carboanhydrase inhibitor.

These properties, along with a virtual non-toxicity, had led to start a considerably wide clinical-test activity, and the compound had been administered in tablets or gelatine capsules, at an average dosage unit of 10 to 100 milligrams of active substance.

At the dosages indicated above, no toxic phenomena were observed in humans, or intolerance of any kind. The diuretic activity, both under normal conditions of hydrosaline balance, and in illnesses which were characterized by a high hydrosaline retention rating, did not appear immediately upon the administration of the drug (contrary to what occurs with other diuretics, such as furosemide), but appeared after 3-6 hours and lasted for a period of time ranging from 24 to 30 hours or more after a single administration.

A phenomenon, which proved to be difficult to explain, had been observed, that is, a certain number of patients, say the 20 percent, for the most part patients whose general conditions were extremely poor, but sometimes also normal patients, did not show to have been influenced in any wise by the treatment. The latter patients, even when treated with gradually higher dosages, up to 50 milligrams, did not respond to the treatment anyhow, whereas they proved to be responsive to other diuretics, such as hydrochlorothiazide, furosemide and ethacrynic acid.

This phenomenon of apparent resistance involved a certain number of patients, whereas it is known that the clinical response of the conventional diuretics is constant.

SUMMARY OF THE INVENTION

In order to overcome the above enumerated defects of 2-phenyl-6-sulphamyl-7-chloro-1,2,3,4-tetrahydro-4-quinazolinone when employed as a diuretic, it has been envisaged to exploit the acidic nature of hydrogen, both in the sulphamyl group and in the 3-position of the heterocyclic ring.

Broadly stated, the invention relates to both the monopotassium- and the dipotassium derivatives of 2-phenyl-6-sulphamyl-7-chloro-1,2,3,4-tetrahydro-4-

quinazolinone, as diuretics. These derivatives are obtained by replacing, for the former, either hydrogen of the sulphamyl group by a potassium atom, and, for the latter, by replacing either hydrogen of the sulphamyl

5 group and the hydrogen lying in the 3-position of the tetrahydroquinazolinone ring by one potassium atom each, respectively. Both the mono- and the dipotassium derivatives are water soluble. A 1 percent aqueous solution of the monopotassium derivative has a pH of about 9.9, and, after a certain period of time a precipitate is observed, which is the starting sulphonamide, a product of hydrolysis. Conversely, the dipotassium derivative yields a stable 1 percent aqueous solution which has a pH of about 11.5.

10 15 The analysis of the monopotassium derivative is as follows:

For $C_{14}H_{11} Cl K N_3O_3S$

20 Found % K = 10.04 % Cl = 9.37 % N = 11.04
Calcd. 10.42 9.44 11.18

The analysis of the dipotassium derivative is as follows:

For $C_{14}H_{10}ClK_2N_3O_3S$

25 Found % K = 18.85 % Cl = 8.17 % N = 9.73
Calcd. 18.88 8.50 9.98

30 35 However, both the mono- and the dipotassium derivatives are best characterized by their IR spectra, as will be set forth in more detail hereinafter.

The foregoing objects, features and advantages of the invention will become apparent to those skilled in the art from the ensuing detailed description of the spectral characteristics of the novel products as depicted in the accompanying drawings, and from a number of both pharmacological and clinical tests which will be reported hereinafter.

40 **DESCRIPTION OF THE DRAWINGS**

In the drawings:

FIGS. 1 and 1a show the IR spectrum of the starting quinazolinone, for comparison purposes.

45 FIGS. 2 and 2a show the spectrum of the monopotassium derivative, and

FIGS. 3 and 3a show the spectrum of the dipotassium derivative.

50 55 For technical reasons, the spectra are divided into two portions, which can be assembled for reading by superposing the common portions, say, of FIGS. 1 and 2a and so forth, as usual. The spectra have been obtained with a Perkin-Elmer Spectrometer.

DETAILED DESCRIPTION OF THE PREFERRED EMBODIMENTS AND THE SPECTRA

60 65 1. The starting quinazolinone, i.e. 2-phenyl-6-sulphamyl-7-chloro-1,2,3,4-tetrahydro-4-quinazolinone has an IR spectrum (FIGS. 1 and 1a shown for comparison) exhibiting two absorption bands at 3420 and 3330 cm^{-1} , which correspond to the asymmetrical and symmetrical stretching -NH_2 of the sulphamyl group, respectively, one band at 1660 cm^{-1} which corresponds to the carbonyl group of the quinazolinone ring (=CO stretching), one band at 1620 cm^{-1} which presumably corresponds to the aromatic ring (-C=C- stretching), two bands at 1335 and 1160 cm^{-1} , corresponding to the asymmetrical and symmet-

rical stretching, $S=O$, of the sulphamyl group, respectively.

2. For the monopotassium derivative, FIGS. 2 and 2a, the bands at 3420, 3330, 1335 and 1160 cm^{-1} disappear, this fact being an evidence of the substitution which has taken place at the sulphamyl group. conversely, the 1655 band, corresponding to the absorption of the carbonyl and the 1605 band, which can be attributed to the aromatic ring, remain. At 1110 (approx.) a very wide band is observed, whose interpretation is difficult.

3. For the dipotassium derivative, the absorption bands at 3420, 3330, 1335 and 1160 cm^{-1} are lacking, and, in addition, the 1655 band, characteristic of carbonyl, is very weakened, thus showing that the second potassium atoms has replaced the cyclic amide, probably for giving rise to an equilibrium of the kind:

The absorption of the aromatic ring at 1610 cm^{-1} , and the wide one at 1105 (whose origin has not been surely identified) remain strong. (See FIGS. 3 and 3a).

Examples of methods for preparing the mono- and the dipotassium derivatives of the starting quinazolinone.

In the following, a few examples of methods for preparing the mono- and the dipotassium derivatives of the starting quinazolinone will be described.

EXAMPLE 1

Method for preparing the monopotassium derivative of 2-phenyl-6-sulphamyl-7-chloro-1,2,3,4-tetrahydro-4-quinazolinone

An appropriate volume of a 5 percent aqueous solution of potassium methoxide (or ethoxide), containing 11.56 grs. (0.296 mol) of potassium was added dropwise, with cooling, to a solution of 100 grs of 2-phenyl-6-sulphamyl-7-chloro-1,2,3,4-tetrahydro-4-quinazolinone in 500 mls of dimethylformamide (DMF).

The monopotassium derivative was precipitated from this solution by adding thereto 5,000 mls of ether. The product was collected on a filter, washed carefully with ether and dried. It was a white crystalline powder showing the InfraRed spectrum of FIGS. 2 and 2a.

EXAMPLE 2

Method for preparing the monopotassium derivative of 2-phenyl-6-sulphamyl-7-chloro-1,2,3,4-tetrahydro-4-quinazolinone

To a suspension of 0.1 mol of 2-phenyl-6-sulphamyl-7-chloro-1,2,3,4-tetrahydro-4-quinazolinone in 600 mls. of anhydrous methanol (or ethanol), cooled at

1°-2°C, there was added dropwise, with stirring, 0.1 mol of a 10 percent solution of potassium methoxide (or ethoxide) in methanol (or ethanol). The potassium alkoxide solution can be conveniently replaced by a 10 percent solution of potassium hydroxide in methanol.

The thus obtained solution of the monopotassium derivative was filtered and evaporated to dryness under reduced pressures.

The product which has been isolated is a white crystalline powder exhibiting an IR spectrum such as that shown in FIGS. 2 and 2a.

EXAMPLE 3

Method for preparing the dipotassium derivative of 2-phenyl-6-sulphamyl-7-chloro-1,2,3,4-tetrahydro-4-quinazolinone

An appropriate volume of a 5 percent solution of potassium methoxide (or ethoxide) in methanol (or ethanol), containing 23.12 grs. (0.592 mol) of potassium, was added dropwise, with cooling, to a solution of 100 grs. of 2-phenyl-6-sulphamyl-7-chloro-1,2,3,4-tetrahydro-4-quinazolinone in 500 mls. of DMF. The dipotassium derivative was precipitated from the solution indicated above by adding 5,000 mls. of ether thereto. The precipitate was collected on a filter, carefully washed with ether and dried.

The final product is a yellow crystalline powder whose IR spectrum is very much the same as that shown in FIGS. 3 and 3a.

EXAMPLE 4

Method for preparing the dipotassium derivative of 2-phenyl-6-sulphamyl-7-chloro-1,2,3,4-tetrahydro-4-quinazolinone

To a suspension of 0.1 mol of 2-phenyl-6-sulphamyl-7-chloro-1,2,3,4-tetrahydro-4-quinazolinone in 600 mls. anhydrous methanol (or ethanol), cooled at 1°-2°C, there was added dropwise, with stirring, 0.2 mol of a 10 percent solution of potassium methoxide (or ethoxide) in methanol (or ethanol). The solution of the dipotassium derivative thus obtained was filtered and evaporated to dryness under reduced pressures. The isolated product is a yellow crystalline powder which is very soluble in water and has an infrared spectrum very much the same as shown in FIGS. 3 and 3a.

EXAMPLE 5

Method for preparing the dipotassium derivative of 2-phenyl-6-sulphamyl-7-chloro-1,2,3,4-tetrahydro-4-quinazolinone.

To a suspension of 0.1 mol of 2-phenyl-6-sulphamyl-7-chloro-1,2,3,4-tetrahydro-4-quinazolinone in 680 mls. distilled water, cooled at 1°-2°C, there are added dropwise, with stirring, 0.2 mol of KOH in an aqueous solution. After a 30-minute stirring, the solution thus obtained was filtered on a glass-wool filter and freeze-dried. A very soft yellow powder is obtained, which is readily soluble in water, with a pH of about 11.5.

RESULTS OF THE PHARMACOLOGICAL AND CLINICAL TEST

Both the potassium derivatives as described hereinabove have been compared, as to their diuretic activities, with the 2-phenyl-6-sulphamyl-7-chloro-1,2,3,4-tetrahydro-4-quinazolinone, hereinafter called "the starting quinazolinone" for brevity.

Contrary to what has been said above in the introductory part of this specification for the starting quinazolinone, the diuretic response of the patients to both the mono- and the dipotassium derivatives was intense and no exception was detected.

The tests which have been carried out have shown that both the potassium derivatives of this invention exhibit an increased diuretic activity over that of the starting quinazolinone. This action is due to a more intensive absorption of the derivatives in question by the system. This exalted absorption is evidenced by a more pronounced elimination through the urinary tract.

A method for dosing in the urines both the starting quinazolinone and the two potassium derivatives of this invention has been envisaged by the applicants and has an accuracy as high as 1 microgram per milliliter.

The outline of the dosage method indicated above is as follows:

The urines are collected at regular intervals and brought to a pH of 8, and repeatedly extracted with ethyl acetate. The latter, dried upon sodium sulphate, is evaporated to dryness and the residue, redissolved in DMF (dimethylformamide), is quantitatively placed on a glass plate carrying a layer of 0.25 mms. of silica gel containing a fluorescent detector. Chromatographic analysis has been carried out by using a 70/30 (by vol.) mixture of chloroform and methanol as the eluant. The quinazolinone spot (this is valid in any case, since in the body both the potassium derivatives restore the starting quinazolinone) can easily be recognized for its R_F (0.7 approx.) and its fluorescence when lighted by a lamp emitting a UV light with a wavelength of 254 millimicrons. The silica gel which contains the product is scraped out, extracted many times with DMF and filtered and the DMF is evaporated under reduced pressures. The residue is then saponified by boiling it during 2 hours with 2 mls. of N/1 NaOH, the resultant solution is acidified with N/1 HCl and the as formed 2-amino-4-chloro-5-sulphamyl-benzamide is evaluated according to the method of Bratton and Marshall (J.Biol.Chem., 128, 537 (1939)), by comparing the color obtained with that of a known amount of the starting quinazolinone which has undergone the same treatment as described just now.

A number of tests have been carried out, both on dogs and humans, in each of which there was administered, in parallel, a certain amount of the starting quinazolinone and, on the other sides, the same amount in the form of the mono- and the dipotassium derivatives of this invention. In all cases, the excreted amount of the starting quinazolinone (in the body, as recalled above, both the potassium derivatives are reconverted

to the starting quinazolinone), was measured with the method which has been outlined herein above.

FIRST SET OF TESTS

5 Tests with the starting quinazolinone, on dogs

Test No. 1

To a dog having a body weight of 8.55 kgs. there were administered 76.9 mgms. of the starting quinazolinone. 72 hours after the administration, the total amount of excreted urine was 1,145 mls. and the amount of starting quinazolinone eliminated with the urines was 13.84 mgms., that is, about the 18 percent. The equivalent unitary dosage was 9 mgms. per kilogram of body weight.

15 Test No. 2

To a dog having a body weight of 9.2 kgs. there were administered 82.8 mgms. of the starting quinazolinone, that which was equivalent to 9 mgms/kg.b.w. The volume of urines as excreted after 72 hours from the administration was 1,600 mls. and the total excreted quinazolinone was 13.77 mgms., equivalent to 16.6 percent of the administered amount.

20 Test No. 3

To a dog weighing 10.3 kgs. there were administered 92.7 mgms. of the starting quinazolinone, equivalent to 9 mgms/kg b.w. The total excreted urine after 72 hours was 1,707 mls., and the excreted quinazolinone was 14.65 mgms., equivalent to the 15.80 percent of the administered amount.

25 Test No. 4

To a dog weighing 7.50 kgs. there were administered 67.5 mgms. of the starting quinazolinone, that which is equivalent to 9 mgms. per kg. b.w. After 72 hours, the total excreted urine was 1,874 mls., containing 15.15 mgms. of the starting quinazolinone, equivalent to the 22.4 percent of the administered amount.

TESTS WITH THE MONOPOTASSIUM DERIVATIVE, ON DOGS

40

In all of these tests, the dosage was 9 mgms. per kg.b.w. The tests have been numbered with an M added to the figure, to recall the monopotassium derivative of this invention.

45 Test No. 1M

A dog weighing 7.5 kgs. received 74.2 mgms. of the product (=67.5 mgms. of starting quinazolinone). After 72 hours, the excreted urine was 2,570 mls., and the starting quinazolinone which had been excreted was 24.5 mgms. (=34.4 percent of the administered amount).

50 Test No. 2M

To a dog weighing 8.3 kgs. there were administered 82 mgms. of the monopotassium derivative, as defined above. This was equivalent to 74.7 mgms. of the starting quinazolinone. The urine excreted after 72 hours was 2,830 mls., and the starting quinazolinone which had been excreted was 27.8 mgms., equivalent to 37.2 percent of the administered amount.

55 Test No. 3M

To a dog weighing 10.5 kgs. there were administered 103.9 mgms. of the monopotassium derivative, equivalent to 94.5 mgms. of starting quinazolinone. The urine excreted after 72 hours was 2,945 mls., the starting quinazolinone excreted was 38.9 mgms., that is, the 41.2 percent of the administered amount.

60 Test No. 4M

To a dog weighing 7.7 kgs. there were administered 76.2 mgms. of monopotassium derivative, as defined

above. This was equivalent to 69.3 mgms. of starting quinazolinone. After 72 hours, the excreted urine was 2,750 mls., and the starting quinazolinone excreted was 22.6 mgms., equivalent to the 32.7 percent of the administered amount.

TESTS WITH THE DIPOTASSIUM DERIVATIVE, ON DOGS

The following tests, from 5D to 8D inclusive, have been carried out with the dipotassium derivative of the invention: the letter D after the figure recalls this fact. Also in this case, the compound which is excreted is the starting quinazolinone: its derivative is never excreted as such.

Test No. 5D

To a dog weighing 8.7 kgs. there were administered 95.7 mgms. of the dipotassium derivative, as defined above, according to the invention. The quantity was equivalent to 78.3 mgms. of the starting quinazolinone. The unitary dose was 11 mgms. of the dipotassium derivative (equivalent to 8 mgms./kg b.w.) of the starting quinazolinone, per kg.b.w.) After 72 hours, the excreted urine had a volume of 2,025 mls and the excreted starting quinazolinone was 33.91 mgms., equivalent to the 43.3 percent of the administered amount.

5 A dog weighing 8.9 kgs. was treated with 97.9 mgms. of the dipotassium derivative, as defined above. This dose is equivalent to 9 mgms./kg.b.w. of the starting quinazolinone. After 72 hours, the excreted urine volume was 2,070 mls., the excreted starting quinazolinone 31.7 mgms., that is, the 39.66 percent of the amount as administered originally.

SECOND SET OF TESTS, ON DOGS, WITH THE STARTING QUINAZOLINONE AND THE TWO POTASSIUM DERIVATIVES THEREOF

10 Under the same conditions as in the tests of the first set, the starting quinazolinone and the mono-, and the dipotassium derivatives were administered to dogs, the unitary dosage (or its stoichiometrical equivalent for each of the potassium derivatives) being 1 mgm./kg.b.w. The results are tabulated below: in the Tables, the tests having no character after their numbers relate to the starting quinazolinone, those having an M after the number relate to the monopotassium derivative, and those having a D after the number relate to the dipotassium derivative.

Test No.	Dog wt. kgs.	Administered amount of start. quinazolinone milligrams	Urine excreted after 72 hrs. milliliters	Starting quinazolinone excreted milligrams	Excreted percentage of the starting quinazolinone %
9	10.4	10.4	745	1.4	13.6%
10	11.6	11.6	730	1.7	14.9%
11	12.4	12.4	695	1.5	12.5%
12	12.6	12.6	810	1.7	13.7
Test No.	Dog wt. kgs.	Administered amount of monopotassium derivative milligrams	Urine excreted after 72 hrs. milliliters	Starting quinazolinone excreted milligrams	Excreted percentage of the starting quinazolinone
13M	8.7	9.5	850	2.9	33.5%
14M	10.3	11.3	1,125	3.6	35.6%
15M	10.9	12	970	3.3	30.3%
16M	11.5	12.6	1,305	3.1	27.3%
Test No.	Dog wt. kgs.	Administered amount of dipotassium derivative milligrams	Urine excreted after 72 hrs. milliliters	Starting quinazolinone excreted milligrams	Excreted percentage of the starting quinazolinone
17D	9.9	12.07	773	2.9	30.1%
18D	13.6	16.6	1,005	3.1	23.1%
19D	10.6	12.9	1,060	3.3	31.7%
20D	11.4	13.9	1,175	3.2	28.7%

Test No. 6D

To a dog weighing 9.3 kgs. there were administered 102.3 mgms. (equiv.to 83.7 mgms of the starting quinazolinone) of the dipotassium derivative of the invention. The total excreted urine after 72 hours was 2,080 mls., and the excreted starting quinazolinone was 37.7 mgms., equivalent to the 45.0 percent of the administered amount. Also in this case the unitary dose was 9 mgms of the starting quinazolinone per kilogram of body weight.

Test No. 7D

To a dog weighing 12.5 kgs. there were administered 137.5 mgms. of the dipotassium derivative, as defined above. This amount is equivalent to 9 mgms. per kg.b.w. of the starting quinazolinone. The The urine excreted after 72 hours was 1,945 mls. and the quantity

55 Also the second set of tests shows, beyond any doubt, the advantages achieved with the use of the potassium derivatives prepared according to the invention over the starting quinazolinone.

THIRD SET OF TESTS, ON HUMANS, WITH THE STARTING QUINAZOLINONE AND THE TWO POTASSIUM DERIVATIVES THEREOF

60 The third set of tests has been carried out on human volunteers. It should be noted that this set is a repetition test, that is, the same volunteers underwent the tests with the starting quinazolinone and then with the two potassium derivatives thereof. The unitary reference dose of starting quinazolinone is about 0.4 mgms. per kg.b.w. for all the tests of the set.

The results are tabulated hereinafter, and the test number code is the same as above.

be understood by anyone skilled in the art, that modifications and changes can be introduced therein without

TESTS WITH THE STARTING QUINAZOLINONE, ON HUMANS.

Test No.	Name (init.)	Wt. kgs.	Administered amount of starting quinazolinone milligrams	Urine excreted after 72 hrs. milliliters	Starting quinazol. excreted milligrams	Percentage of excreted quinazolinone %
21	Mr.F.P.	75	30	2,060	6.1	20.4%
22	Mr.R.F.	82	30	1,150	5.9	19.9%
23	Mr.C.G.	73	30	1,995	5.6	18.7%
24	Mr.P.G.	68	30	1,835	6.3	21.1%

TESTS WITH THE MONOPOTASSIUM DERIVATIVE, ON HUMANS.

Test No.	Name (init.)	Wt. kgs.	Administered amount of monopotassium derivative milligrams	Urine excreted after 72 hrs. milliliters	Starting quinazol. excreted milligrams	Percentage of excreted quinazolinone %
21M	Mr.F.P.	75	33	2,350	9.9	33.2%
22M	Mr.R.F.	82	33	2,120	8.2	27.5%
23M	Mr.C.G.	73	33	2,420	10.6	35.4%
24M	MR.P.G.	68	33	2,080	7.8	26.3%

TESTS WITH THE DIPOTASSIUM DERIVATIVE, ON HUMANS.

Test No.	Name (init.)	Wt. kgs.	Administered amount of dipotassium derivative milligrams	Urine excreted after 72 hrs. milliliters	Starting quinazolinone excreted milligrams	Percentage of excreted quinazolinone %
21D	Mr.F.P.	75	36.7	2,450	10.4	34.8%
22D	Mr.R.F.	82	36.7	2,600	9.9	33.2%
23D	Mr.C.G.	73	36.7	2,255	7.6	25.4%
24D	Mr.P.G.	68	36.7	2,695	11.4	38.3%

The above reported clinical tests, made for comparison on the same persons, show that the amount of the diuresis, as well as the excreted quantity of the starting quinazolinone is always greater, whenever the potassium derivatives are administered rather than the starting quinazolinone as such.

In the clinical practice, it has been ascertained that the minimum diuresis-promoting unit dose for humans is, for both the monopotassium and the dipotassium derivatives as hereinbefore defined, in the vicinity of 0.1 milligrams per kilogram of body weight, and that the average therapeutic dose is 0.3 – 1 milligram per kilogram of body weight.

While the invention has been described in connection with a few preferred embodiments thereof, it will

departing from the scope of the invention as defined in the claims appended hereto.

What is claimed is:

1. As a novel, nontoxic, nonmercurial diuretic compound, the derivative of 2-phenyl-6-sulphamyl-7-chloro-1,2,3,4-tetrahydro-4-quinazolinone, wherein either hydrogen of the sulphamyl group of the starting quinazolinone is replaced by a potassium atom.
2. As a novel, nontoxic, nonmercurial diuretic compound, the derivative of 2-phenyl-6-sulphamyl-7-chloro-1,2,3,4-tetrahydro-4-quinazolinone, wherein either hydrogen of the sulphamyl group of the starting quinazolinone and the hydrogen in the 3-position of the tetrahydroquinazoline ring of same starting quinazolinone are replaced by a potassium atom each.
